INDICATING MEANS FOR SWITCH
MACHINESAndrew Langdon, Rochester, N. Y., assignor to
General Railway Signal Company, Rochester,
N. Y.

Application October 30, 1930, Serial No. 492,282

3 Claims. (Cl. 246—253)

This invention relates to indicating circuits for railway switch mechanisms and more particularly to a means for indicating the condition of a switch by local energy over a polarized circuit.

When such machines are operated electrically and controlled from a remote point, it is desirable to have at the control point a knowledge of the existing position of the switch points at all times. In a conventional all electric switch operating arrangement, the extreme position of the switch points and the integrity of the switch locking is checked by the indicating means through an incorporated point detector arrangement similar to the one shown in the patent to C. S. Bushnell No. 1,517,236, dated November 25, 1924.

There are also certain types of switch machines which do not include the above mentioned point detector arrangement and consequently an indication of the position of the switch machine contacts is not necessarily indicative of the switch point position, because through some disruption of the switch operating connection the position of the switch points may not correspond to the condition of the switch machine.

With the above and other considerations in mind, it is proposed in accordance with this invention, to provide an indicating system employing the usual switch machine pole changer contacts in combination with an auxiliary circuit controller operated directly by the movement of the switch points.

Other objects, purposes and characteristic features of the invention will appear as the description thereof progresses, during which reference will be made to the accompanying drawing, which illustrates diagrammatically the indicating circuit for a switch operating arrangement in accordance with this invention.

Referring to the accompanying drawing, a section of a railroad track T is shown with a track switch TS governing the movement of traffic either in a straight or a diverging route. The switch TS is electrically operated by a switch machine SM, which is indicated by a dotted rectangle in which the pole changer arrangement is shown, but other parts of the machine which are clearly shown in the patent to W. K. Howe, No. 1,466,903, dated September 4, 1923, and do not concern this disclosure, are omitted. The pole changer is represented by stationary pairs of contacts 1, 2, 3 and 4 which are engageable by the shunting blocks 5 and 6 as shown, which are shifted to

a normal and a reverse position at the end of each corresponding operating stroke.

A circuit controller C is directly coupled to the switch TS so as to operate in accordance with the movement thereof and can be of any suitable type, such for example as shown in the application of O. S. Field, Ser. No. 437,445, filed March 20, 1930. The type of controller illustrated includes four movable contact fingers 7, 8, 9 and 10 which are engageable with stationary contacts 11—18 and which are so adjusted that the contact arms 7 and 8 are shunted and likewise contact arms 9 and 10 are shunted, at all times except when the switch points are in either of their extreme positions or a short distance, say one quarter of an inch, therefrom. A local source of energy is provided by battery B which energizes a three position relay WP, which operates contacts as shown, to control signals or functions associated with the switch TS, and is controlled over a polarized circuit including the pole changer contacts and the switch circuit controller contacts as is more fully described hereinafter. The source of energy can be alternating current with a three position alternating current relay, but for convenience is shown to be direct current.

It is believed that the present invention can be more readily understood by further description being given to the particular circuit employed from the standpoint of the operation thereof.

Assuming that the track switch TS has been operated to its normal position, as shown, the signal control relay WP is energized with a definite polarity by the local battery B over the following circuit:—beginning at the positive side of battery B, wires 19 and 20, contacts 2 shunted by block 6, wires 21 and 22, contact 15, contact finger 9, wire 23, winding of relay WP, wire 24, 40 contact finger 10, contact 17, wires 25 and 26, contact 13, contact finger 8, wire 27, contact finger 7, contact 11, wires 28, 29 and 30 back to negative side of battery B.

The signal control relay WP, in like manner, is operated to its reverse position when the switch TS is operated to its reverse position as the shifting of the pole changer contacts and the switch circuit controller contacts to their reverse or the indicated dotted position applies an opposite polarity of energy to the windings of the relay WP over the following circuit:—beginning at the positive side of battery B, wire 19, contacts 4 shunted by block 6 in its dotted position, wires 34 and 31, contact 18, contact 55

finger 10 in its dotted position, wire 24, winding of relay WP, wire 23, contact finger 9 in its dotted position, contact 16, wires 26 and 33, contact 12, contact finger 7 in its dotted position, wire 27, contact finger 8 in its dotted position, contact 14, wires 32, 28, 29 and 30 back to the negative side of battery B.

In the event that an abnormal condition exists at the switch which prevents the movement 10 of the switch points to their proper extreme position, the relay WP is shunted by the switch circuit controller C at contact fingers 9 and 10 which are adjusted, as previously described, to shunt through contacts 16 and 17 which are connected by wire 25. The shunt on the windings of relay WP is comparatively of low resistance which assures a deenergized or neutral position even in the event of other energy being abnormally superimposed on the relay windings. 20 It is also evident from the drawing that the circuit from the switch machine pole changer is interrupted at contacts 11, 14, 15 and 18 which prevents the shunting of the battery B under the above conditions.

If the switch machine SM operates the switch TS to its proper extreme position, for example the reverse position, and thereby properly operates the switch circuit controller C to its reverse or indicated dotted position, but fails to lock the switch in such a position, the shunting blocks 5 and 6 consequently do not shift and the relay WP is shunted as before over the following circuit:—Beginning at the winding of relay WP, wire 24, contact finger 10 in its dotted position, contact 16, wire 31, contacts 1 shunted by block 35 5, wires 28 and 32, contact 14, contact finger 8 in its dotted position, wire 27, contact finger 7 in its dotted position, contact 12, wires 33 and 26, contact 16, contact finger 9 in its dotted position, wire 23, to the opposite side of the winding of the relay WP.

The relay WP is likewise shunted when a condition converse to the above exists, or namely when the track switch TS is operated to its proper normal position but the switch machine SM fails to lock in the normal position. This is accomplished over a circuit which, because of its similarity to the one just traced, is readily evident from the drawing and will not be described in detail.

It is now evident that the relay WP accurately repeats the condition of the switch TS and checks the proper movement of the switch points as well as the locking of the switch machine SM. 55 In other words, the relay WP definitely responds to a polarity of energy which is in accordance with the switch position and at such times as the switch is not assuming a predetermined position in respect to safety, and when the switch is not locked in such a position, the relay is deprived of energy and as a further precaution is shunted against a false operation by foreign energy. It is also evident that the integrity of this shunting circuit is checked by the energizing circuits for the relay WP, as for example, the normal energizing circuit includes the circuit whereby the relay WP is shunted when the switch points are not in their proper extreme

position, and the reverse energizing circuit includes the circuit whereby the relay WP is shunted when the switch circuit controller and the pole changer are not in corresponding positions.

Having shown and described one specific embodiment of the present invention, and having shown it as including a single circuit arrangement, it is desired to be understood that this circuit arrangement has been shown with the idea that it is merely typical of several circuit arrangements which may be employed all without departing from the scope of the invention or the idea of means underlying the same.

Having thus described my invention, what I claim is:

1. In combination, a track switch, a switch machine arranged to power operate said track switch, pole changer contacts included in said switch machine and operated in accordance with the locked position thereof, a switch circuit controller directly operated in accordance with the position of said track switch, a local source of energy at said track switch, a three position polarized relay, a control circuit including said switch machine pole changer contacts and said switch circuit controller for distinctively operating said relay in accordance with the extreme position of said switch and the locked position of said switch machine, and means for shunting said relay when said switch circuit controller is not in either extreme position and also when said extreme position does not correspond to the position of said switch machine pole changer contacts.

2. An indicating system including a track switch, operating mechanism for said track switch including pole changer contacts actuated by the locking movement thereof, a switch circuit controller operated directly by the movement of said track switch, an electrical indicating circuit controlled by said pole changer contacts and said switch circuit controller, said pole changer and said switch circuit controller cooperating to pole change said control circuit according to the extreme locked position of said track switch, and also cooperating to shunt said control circuit when not in either extreme position and also when said track switch position is out of correspondence with said pole changer position.

3. In an indicating system including a track switch, operating mechanism for said track switch including pole changer contacts for pole changing a complete circuit and actuated by the locking movement thereof, a track switch circuit controller operated directly by the movement of, and through the power of said track switch, three wires only interconnecting the pole changer contacts and the circuit controller, an electrical indicating circuit controlled by said pole changer contacts and said switch circuit controller, said pole changer and said switch circuit controller cooperating to pole change said control circuit according to the extreme locked position of said track switch.

ANDREW LANGDON.
